UNITED STATES PATENT OFFICE

WALTER C. FAIN, OF NORFOLK, VIRGINIA, ASSIGNOR TO WAINSLO MANUFACTURING CORPORATION, OF NORFOLK, VIRGINIA

COLLAPSIBLE FURNISHINGS

Application filed October 20, 1928. Serial No. 313,817.

The present invention relates to household furnishing of the folding type which is capable of assuming a normal operative position in the room during use and of collapsing and folding away into a restricted compact area, such as against a wall, when in disuse, and has particular reference to folding sets of this general character comprising, for example, a table and associated benches.

In modern apartments and small homes conservation of space has become a vital necessity, there being a growing tendency to use one room for a number of different purposes. Thus, the living room has been called upon to perform the duties of a dining room and, in some instances, to serve as a bedroom as well. In the interests of this forced space conservation, various types of folding, collapsing and disappearing furniture have had their conception and development. Among the most important types of such furniture is the so-called breakfast set, normally comprising a table and two associated benches, so constructed and assembled as to occupy a horizontal position extending into a room when in use, and capable in disuse of being folded flat against a wall or other supporting surface and thereby, insofar as space and conspicuity are concerned, effectively removing the set from the room in which it is used. While performing a most useful function, prior breakfast sets have not proven to be entirely successful in a practical way and several well-known defects and disadvantages have become apparent to both manufacturer and user. One of the chief disadvantages is the difficulty of folding and extending the assembled sets from the inoperative position to the position occupied during use and vice-versa. To be entirely successful, the sets must lend themselves to extension and folding without the exercise of substantial muscular effort, as the sets are operated for the most part by housewives. It is likewise essential that the sets be constructed and assembled so

as to render the folding and extending operations orderly, simple and fool-proof, and this has been lacking to a noticeable degree in previous furniture of this type.

A general object of the present invention is to provide an improved breakfast set in which the disadvantages referred to are eliminated. The invention contemplates the provision of a three-piece breakfast set capable of folding against a vertical wall, door, or other exposed surface, and having the parts thereof so constructed and assembled as to permit the extending and folding operations to be accomplished with a minimum amount of physical effort, and which in addition may be quickly and semi-automatically manipulated.

A further object is to provide a folding breakfast set which is simple in construction, relatively inexpensive to manufacture and durable and serviceable in use.

These and other features of the invention will be apparent from the following detailed description when read in connection with the accompanying drawings, and will be pointed out in the appended claims.

In the drawings:

Fig. 1 is a perspective view of the invention, the table and benches occupying the normal operative position;

Fig. 2 is a side view thereof;

Fig. 3 is a front elevation with the parts in a partly folded condition;

Fig. 4 is a side view of the parts shown in Fig. 3 and looking from left to right;

Fig. 5 is a section on line 5—5 of Fig. 3;

Fig. 6 is a horizontal section along line 6—6 of Fig. 3 with the parts completely folded;

Fig. 7 is a partial front elevation on an enlarged scale;

Fig. 8 is a side view of the parts shown in Fig. 7;

Fig. 9 is a detail of the table latch;

Fig. 10 is a section on line 10—10 of Fig. 3; and

Fig. 11 is a section on line 11—11 of Fig. 3.

Referring more particularly to the drawings, the reference character 10 indicates a support adapted to be rigidly and permanently attached to any convenient vertical stationary support such as a wall 11. The support is generally rectangular in shape and 10 may be of solid formation or, as illustrated, in the form of a frame having horizontal top and bottom rails 12 and 13 and vertical side members 14. Each side member is provided with a relatively thick jamb 15, the upper 15 face of which lies in a plane substantially flush with the upper edge of the top of the frame for a purpose hereinafter described.

A table 16 is pivotally mounted upon the upper rail 12 of the support by means of 20 hinges 17, the connection between the table and the support being such that the former may be moved into a vertical plane in alignment with the plane of the support and in substantial flat contact with the wall 11, as 25 illustrated in Figs. 3 and 4, or may be moved about its pivot into a horizontal plane as clearly illustrated in Figs. 1 and 2. The particular form and shape of the table is not important and may be varied to conform with 30 the tastes of the user and the needs of a particular installation. When occupying a horizontal or operative position, the table rests at its inner end on and is therefore supported by the upper faces of the jambs 15, the outer portion of the table receiving its 35 support from a leg 18 hinged to the bottom of the table as at 19, the hinge being arranged to permit the leg folding against the bottom of the table and in close proximity thereto. 40 Each side of the table leg is cut away as at 20 to permit compact folding of associated parts in the manner hereinafter described. The leg 18 is connected to the support 10 by a rigid rod 21, the latter being pivoted at 22 to the top 45 rail of the support, and at 23 to the inner side of the leg. This rigid connection between the leg and the support serves to maintain such parts in parallelism at all times, irrespective of whether the leg is in a vertical completely 50 collapsed position, in an active supporting position, or in intermediate positions. By such a connection, the leg is forced to assume and maintain a position at right angles to the table when the latter is extended, 55 thereby insuring a safe and reliable support. The rod connection also serves to automatically fold and unfold the leg when the table is moved from one position to another, no assistance from the operator being required to 60 move or position the leg. To avoid interference between the table leg and the rod 21 when the former is moved into folded position, the inner surface of the leg is provided 65 with a groove 24 for receiving the rod. It will be noted that the adjacent end of the

groove extends beyond the pivotal connection 23 between the rod and the table so that the rod may enter the groove throughout substantially its entire length.

Bench units indicated generally at 25 are mounted on each side of the table, these units being independent of and unattached to each other and the table. The bench units are identical in form, operation and construction and for this reason a detailed description of one unit only will be given. The unit consists of a bench or seat member 26, supporting legs 27 and a carrying member 28. The carrying member is provided along one edge with brackets 29 having alined openings 30 formed therein for loosely receiving a vertical rod 31 rigidly mounted in corresponding brackets 32 attached to the jamb 15. The carrying member is thus capable of a pivotal movement in a horizontal plane around the rod 31 and a vertical sliding movement axially along the rod. The upper edge of the rod projects beyond the top bracket 32 and the tip thereof is rounded as at 33.

The seat 26 is hinged to the upper edge of the carrier member at 34, the hinges being arranged to permit the seat to assume an inoperative position in the same vertical plane and in alignment with the carrier member, as illustrated in Figs. 3 and 4, and to occupy an active or operative position at right angles to the carrier member and in a horizontal plane adjacent the table as illustrated in Figs. 1 and 2. At a point along its inner edge and spaced from the bottom end, the seat member is provided with a bracket 35 having a shallow socket 36 (see Fig. 7) adapted to be brought into registry with the rod 31 when the seat member and carrier are vertically alined. When the upper end of the rod enters the socket 36, the seat member and carrier will be locked in alined relation, and may then be swung as a unit about the rod as a pivot. To engage and disengage the rod from the socket for the purpose of locking or releasing the seat member, the seat member and carrier are lowered or lifted vertically to shift the parts between the solid and dotted positions indicated in Fig. 7. Sufficient vertical movement between the seat member and carrier and the rod must be permitted to allow clearance between the end of the rod and the socket, but it is preferable to restrict such movement in such a manner that the upper bracket 35 will never strike the table. To this end, an additional stationary bracket 37 is mounted on the jamb above the upper bracket 29 of the carrier member, such brackets being arranged to contact shortly after the socket in the bracket 35 is clear from the upper end of the rod. While the additional bracket 37 may be located at other places along the rod, such as above the lower bracket of the carrier member, its location at the point illustrated is

desirable because it also serves to reinforce the central portion of the rod and prevents flexing and bending thereof at an otherwise unsupported portion.

5 The seat member 26 is supported in its active position by legs 27 hinged to the bottom of the seat at 38 in such a manner as to be folded against the seat and carrier member respectively when such parts are in vertical alinement. The legs are rigidly connected by means of a rod 39, which maintains them in constant parallelism. The ends of the connecting rod are pivoted on a stud 40 upon a bracket 41 attached to the rear face 15 of each leg. The legs move in unison from folded to unfolded position when the seat member is raised or lowered, such movement of the legs being fostered automatically in each instance by gravity.

20 It is important to note that in use the seat is supported wholly and alone by the legs. The carrier member does not contact with the floor and never functions as an active support for the seat. The hinge connection 25 between the seat and the carrier member bears no portion of the weight when the seat is used. The principal function of the carrier member is to hinge the bench unit to the main support so that the horizontal folding 30 of the parts may be accomplished, and in addition, it serves as a cover for the lower portion of the bench unit when the latter is folded flat against the wall.

In disuse, the set is folded against the 35 wall or other surface to which the main support is attached, the parts assuming the position indicated in Fig. 6 and in dotted lines in Fig. 1. The table 16 is flat against the wall and in alinement with the support 40 10, the leg of the table being folded against the bottom thereof. The bench units, having the seat and carrier in alinement and as effective continuations of each other, are folded over the table, the legs of the seats 45 fitting within the cut out portions 20 of the table leg. The space occupied by the folded set corresponds generally to the combined thickness of the table, the legs, and the seat.

To eliminate danger of accidental or unintentional unfolding of the set, it is preferable 50 to provide suitable catches or latches for holding the parts in folded position. To this end a spring clip or fastener 42 is attached to the wall in position to releasably engage the table and retain the latter in vertical folded position. Adjacent surfaces of the table and seats are provided with complementary parts 43 and 44 of a separable fastener 45, such as an elbow latch, to lock the 55 bench units against the table and in folded relation therewith.

Although the component parts of the set are intimately associated, it will be noted that 60 each unit is capable of individual manipulation. Each unit is folded and unfolded in-

dependently of the others and each may be brought into its horizontal operative position while the others remain flat against the wall. Aside from this flexibility in use, it will also be appreciated that the individual 70 manipulation of the single units demands a minimum amount of effort, less than one-third of the force being required as would be the case were the units connected for simultaneous operation. 75

Having thus described the invention, what I claim as new and desire to secure by Letters Patent of the United States is:

1. In combination, a support adapted to be attached to a wall or similar surface, a table hinged to said support so as to be capable of movement to a vertical position in alinement therewith and into a horizontal position at right angles to the support, means to support the table in a horizontal position, 80 a bench unit mounted on the support on each side of said table, each bench unit comprising a carrier member connected to the support by a vertical pivot to swing in a horizontal plane, the said carrier member being vertically movable with respect to said support, a seat hinged to said carrier to swing into a vertical position in alinement therewith and into a horizontal position at right angles thereto, means independent of the carrier member for supporting the seat when in horizontal position, and means for locking the seat and carrier member in alined position, the said locking means being engaged and disengaged by the vertical movement of 90 the carrier member. 95

2. In combination, a support adapted to be attached to a wall or similar surface, a table hinged to said support so as to be capable of movement to a vertical position in alinement 105 therewith and into a horizontal position at right angles to the support, means to support the table in a horizontal position, a bench unit on each side of said table, each of said units comprising a carrier member, a vertical rod secured to the side of said support, brackets secured to the edge of the carrier member adjacent the support, the said brackets having aligned vertical bores for receiving the said rod, a seat hinged to the carrier member so 110 as to occupy a vertical position in alinement therewith and a horizontal position at right angles thereto, foldable legs pivoted to the seat for supporting the latter in horizontal position independent of the carrier member, a bracket secured to the seat having a socket 115 in alinement with the rod when the table and carrier member are in vertical positions, the said socket being adapted to receive the upper end of said rod and retain the carrier and 120 seat in vertical alinement. 125

3. In combination, a support adapted to be attached to a wall or similar vertical surface, a table, a hinge connection between the inner end of the table and the top of said support 130

to permit the table to swing into a vertical position against the wall and in alinement with the support and in a horizontal position at right angles to said support, means independent of the hinges for supporting the hinged end of the table when the latter occupies a horizontal position, a foldable leg for supporting the outer end of the table in horizontal position, a bench unit mounted on said support at each side of said table, the said bench units comprising a carrier member hinged to said support by a vertical rod, the said carrier member being slidable vertically along said rod, a seat hinged to the carrier member to swing into a vertical position alined therewith and into a horizontal position at right angles thereto, legs hinged upon the bottom of the seat members and adapted to be folded thereagainst, the said leg members extending below the carrier member into contact with the floor when the seat is in horizontal position and thereby remove the weight of the seat from the carrier member, and a bracket on the bottom of the seat having a socket adapted to engage the upper end of the vertical rod to lock the seat and carrier member in vertical alined positions, the bench units being adapted to fold as a unit over the table when the latter is in vertical alinement with its support.

4. In combination, a support adapted to be attached to a wall or similar vertical surface, a table, hinge connections between the inner end of the table and said support to permit the table to swing into a vertical position against the wall and in alinement with the support and in a horizontal position at right angles to said support, means independent of the hinges for supporting the hinged end of the table when the latter occupies a horizontal position, a foldable leg for supporting the outer end of the table in horizontal position, means for automatically folding and unfolding the leg when the table is moved from its horizontal to vertical positions, a bench unit mounted on said support at each side of said table, the said bench units comprising a carrier member hinged to said support by a vertical rod, the said carrier member being slidable vertically along said rod, a seat hinged to the carrier member to swing into a vertical position alined therewith and into a horizontal position at right angles thereto, legs hinged upon the bottom of the seat members and adapted to be folded thereagainst, the said leg members extending below the carrier member into contact with the floor when the seat is in horizontal position and thereby remove the weight of the seat from the carrier member and the support, means for simultaneously folding and unfolding the legs of each seat in unison when the seat is moved from horizontal to vertical positions and vice versa, and a bracket on the bottom of the seat having a socket adapted to engage the upper

end of the vertical rod to lock the seat and carrier member in vertical alined positions, the bench units being adapted to fold as a unit over the table when the latter is in vertical alinement with its support.

5. In combination, a vertical support, a table, hinge means connecting the table and the support whereby the table may be folded into an inoperative position in substantial alignment with said support and into an operative position in a horizontal plane at right angles to said support, means for supporting the table in operative position, a bench unit mounted on said support, the said unit comprising a carrier member, a seat member, hinge means connecting said seat member endwise to said carrier member whereby said seat member may assume an inoperative position in vertical alignment with the carrier member and an operative position at right angles to the carrier member, and a leg hinged to the bottom of the seat member, said leg extending below the carrier member and adapted to rest on the floor when the seat member occupies a horizontal position, said leg being hinged to said seat member at a point spaced from the hinge point of said seat member by a distance at least as great as the difference in length between said carrier member and said leg, means pivotally connecting said carrier member to said support whereby said carrier member may swing in a horizontal plane and the seat member, carrier member and leg may as a unit fold over and overlie the table when the latter is in alignment with the support.

6. In combination, a vertical support adapted to be attached to a wall or similar surface, a table, means for hinging the inner end of the table to the support whereby the table may be moved vertically into an inoperative position in substantial vertical alignment with said support and against the wall and into an operative position in a horizontal plane at right angles to said support, means for supporting the table in operative position, a bench unit mounted on said support on each side of the table, each of said units comprising a carrier member, a seat member, hinge means connecting said seat member endwise to said carrier member whereby said seat member may assume an inoperative position in vertical alignment with the carrier member and an operative position at right angles to the carrier member, inner and outer legs hinged to the bottom of the seat members adapted to fold against the bottom of the seat members, said legs extending below the carrier members and adapted to rest on the floor when the seat members occupy horizontal positions, said leg members being hinged to said seat members at points spaced from the hinge points of said seat members by distances at least as great as the difference in length between said

carrier members and said legs, and means for causing the legs of each seat member to move in unison from folded to unfolded positions, means pivotally connecting said carrier member to said support whereby said carrier member may swing in a horizontal plane and each seat member, carrier member and legs may fold as a unit and overlie the table when the latter is in alignment with the support.

7. In combination, a vertical support adapted to be attached to a wall or similar surface, a table, hinge means connecting the inner end of the table and the top of the support whereby the table may be moved vertically into an inoperative position against the wall in substantial alignment with said support and extended into an operative position in a horizontal plane at right angles to said support, means to support the table in operative position, a bench unit mounted on said support on each side of said table, each of said units comprising a carrier member, a seat member, hinge means connecting said seat member endwise to said carrier member whereby the seat member may move into an inoperative position in substantial vertical alignment with the carrier member and into an operative position at right angles to the carrier member, means independent of the carrier member for supporting the seat in its operative position, means for locking the carrier member and seat together as a unit when such parts are in vertical alignment, means pivotally connecting said carrier member to said support whereby said carrier member may swing in a horizontal plane and the bench units may swing in opposite directions relative to the support and overlie the folded table.

8. In combination, a vertical support adapted to be attached to a wall or similar surface, a table, hinge means connecting the inner end of the table and the top of the support whereby the table may be moved into a vertical position in alignment with the support and substantially in contact with the wall, means independent of said hinges for supporting the end of the table adjacent to the vertical support when the table occupies a horizontal position, a leg for supporting the opposite end of the table, hinge means connecting said leg to the bottom of said table whereby the leg may be folded against said bottom, a bench unit mounted on said support on each side of the table, each bench unit comprising a carrier member, a seat member and seat supporting legs, means connecting the seat member to the carrier member whereby such members may be arranged in vertical alignment, means connecting the legs to the seat member whereby the legs may be folded against the bottom of the seat member when the latter is in alignment with the carrier member, said leg members being hinged to said seat member at points spaced

from the hinge point of said seat member by distances at least as great as the difference in length between said carrier member and said legs, means connecting the carrier member to the support whereby the carrier member may swing about a vertical axis, and the seat and carrier member may swing in a horizontal plane as a unit and fold over the table when the latter is positioned against the wall.

9. In combination, a support, a table, hinge means connecting said table at one end to said support whereby the table may swing to a vertical inoperative position and to a horizontal operative position, a leg pivotally mounted adjacent the other end of said table on the lower side thereof, bench units mounted on said support on either side thereof, said bench units comprising carriers, seats, hinge means connecting said seats endwise to said carriers whereby said seats may swing to a vertical inoperative position and to a horizontal operative position, legs pivotally mounted adjacent the outer ends of said seats and on the lower sides thereof, hinge means connecting said carriers to said support whereby said carriers and seats may swing about vertical pivots and be folded as units to overlie said table and support and whereby in folded position said seats are spaced from said table by a distance substantially equal to the thickness of said legs, all parts of the legs on the table and on each seat which lie in the same horizontal plane when the seats and table are swung to vertical positions being spaced by different horizontal distances from the axes of the pivots of said carriers, whereby said legs on the table and on the seats may lie in the same vertical plane when the table and seats are in vertical position and the carriers and seats are swung to position to overlie the table and support.

10. In combination, a support, a table, hinge means connecting said table at one end to said support whereby said table may swing to a vertical inoperative position in alignment with said support and to a horizontal operative position, a leg pivotally mounted adjacent the other end of said table on the lower side thereof, bench units mounted on to said support on either side thereof, said bench units comprising carriers, seats, hinge means connecting said seats endwise to said carriers whereby said seats may swing to vertical inoperative positions in alignment with said carriers and to horizontal operative positions, inner and outer legs pivoted to said seats and on the lower sides thereof, hinge means connecting said carriers to said supports whereby said carriers and seats may swing about vertical pivots and may be folded as units to overlie said support and table and whereby in folded position said seats and carriers are spaced from said support and table by a distance substantially equal to the thickness of said legs, all parts of the

legs on the table and on each seat which lie in the same horizontal plane when the seats and table are swung to vertical positions being spaced by different horizontal distances 5 from the axes of the pivots of said carriers, whereby said legs on the table and on the seats will be completely in alignment with one another in a horizontal direction perpendicular to the face of the support when 10 the carriers are swung to overlie the support, whereby all of said legs may lie in the same vertical plane.

In testimony whereof, I have hereunto set my signature.
